UNITED STATES PATENT OFFICE.

HERBERT EDGAR TAYLOR, OF COVENTRY, ENGLAND.

APPARATUS FOR GENERATING GEAR TEETH.

Application filed July 24, 1923. Serial No. 653,453.

To all whom it may concern:

Be it known that I, HERBERT EDGAR TAYLOR, a subject of the King of England, residing at Coventry, in the county of Warwick, England, have invented certain new and useful Improvements in the Apparatus for Generating Gear Teeth, of which the following is a specification.

My invention relates to machines for the generation of those gear teeth which extend in involute curves along the blank and are of uniform normal pitch from end to end. The object of the invention is to provide a simple and accurate mechanism which will cause the acting end of the tool to trace out the desired involute path.

The invention comprises a method for generating gear teeth for a gear system having as its basis a crown wheel whose teeth extend along involute curves and are of uniform normal pitch from end to end, and consists in rolling the gear blank in the path it would follow if meshed with the said basic crown wheel, while acting upon it by means of a tool of rack form which sweeps out an involute curve corresponding to the curve of the teeth on said basic crown wheel.

Preferably the tool is carried by a slide movable along an arm which oscillates about a fixed point, during which oscillation the slide is acted upon by a cam which varies the acting radius of the tool in such manner that, instead of moving in the arc of the circle, it traces out the desired involute path.

For cutting double involute gears two of these slides are employed, and when appropriately mounted form a double cutting head, each slide being actuated by appropriate mechanism.

The manner of carrying out the invention is illustrated in the accompanying drawings, in which

Figure 1 is a front elevation of the tool holder, the point of the tool moving in a plane parallel to the paper,

Figure 2 is a part-sectional side elevation of Figure 1,

Figure 3 is a part plan view as seen from above, and

Figure 4 is a view similar to Figure 1, but showing an alternative form of cam.

In carrying out the invention, the arm A, by means of the shaft A² is pivotally mounted upon a fixed part B which latter, however, is adjustable in relation to the axis of the blank to be acted upon. Lengthwise upon

the arm A are guide members A³ for a slide C on which are mounted the tool holder C² and tool D of rack form. The direction of motion of the slide C is lengthwise of the arm A, that is, radially of the pivot axis, and its relative sliding movements are controlled by means of a cam carried by the fixed part B and engaging a stud or roller C³ or the like, on the slide C.

Any suitable type of cam may be adopted to control the movement of the slide radially, and in the construction illustrated it is constituted by the formation of a suitably curved slot E² in a plate E which is carried by the fixed part B in a plane parallel to that in which the arm A swings, and is interchangeable with other equivalent plates arranged to suit the various sizes of gears to be cut, and in accordance with the distance of the pivotal axis of the arm A from the axis of the blank upon which the tool D acts. The roller C³ upon the slide C engages in the cam slot E² and ensures positive reciprocations of the slide, and preferably, although a simple roller C³ is shown, its arrangement would be of a known kind adapted to avoid a grinding effect on the cam.

It will be seen that the curved slot E² differs but slightly from the arc of a circle inasmuch as the axis of the shaft A² is located at a position such that a curve struck from it would conform very closely to the involute curve which it is desired to produce. A slight step is provided at E³ in the cam slot, and the portion seen to the left of this in the drawing is the acting part which forms the involute curve, while the portion to the right is an extension concentric with the axis of the shaft A² and merely provided to allow for the swing of the arm A⁴.

To operate the slide-carrying arm A, it is extended upon the side of the pivot A² remote from the slide C, and for constructional reasons this extension is separate from the arm A and is constituted by another arm A⁴ fixed to the shaft A² at some distance from the slide C. At the free end A⁵ of the arm A⁴ it is connected by means of a link (not shown) to any appropriate form of driving mechanism.

The tool with its actuating mechanism is adapted to be used upon a machine in which the blank is arranged to rotate upon its own axis and also to perform a rolling motion around an axis corresponding to that of the

standard crown wheel or equivalent thereof with which it would be adapted to gear.

The embodiment of the invention as above described is of a simple form and can be constructed in a sturdy manner adapted to reduce wear and to avoid slackness, and is suitable for cutting single or double involute gears (i. e., those in which the teeth incline one way only, or in two ways forming chevrons), but it is to be understood that the manner of operating the slide and the arrangement of the mechanism therefor is not limited to the construction above described.

15 Thus, for example, as shown in Figure 4, the cam may be constituted by an annular disc F coaxial with the point of oscillation of the arm A, and the acting part of its outer periphery may be shaped in the manner above described for the curved slot E².
20 Rollers G, G² upon the slide C would engage opposite sides of the cam F to cause the movement of the slide, and one of these rollers G² would be pressed by the spring 25 G³ against the cam to follow up the movements of the slide and prevent any shake in it.

Where double involute teeth are to be cut, two oscillating tool holders, as above described, are employed, one to effect the part of the tooth having the right-handed sweep, and the other for the left-handed sweep, each holder being located about an appropriate axis of oscillation to effect this. The 35 movement of both tools would be timed so that they and their tool slides cleared one another throughout their respective travels.

What I claim as my invention and desire to secure by Letters Patent of the United 40 States is:—

1. In a device for the generation of

curved gear teeth, the combination of a member adapted to oscillate about a relatively fixed axis, a tool holder slideable upon said member toward and away from said fixed axis, a rack tool mounted in said holder, a stationary member and means on said tool-holder adapted to cooperate with the said stationary member so as to reciprocate said tool holder upon said oscillating member 45 during its oscillatory movement, thereby to cause said tool to sweep out the desired curved path.

2. In a device for the generation of curved gear teeth, the combination of an arm adapted to oscillate about a relatively fixed point, 50 a tool holder slideable along said arm, a rack tool mounted in said holder, a stationary cam having an acting face curved about said fixed point in accordance with the desired curved path of said tool, and a member upon said tool slide which engages the acting face of said cam during the operative movement of said tool, thereby to cause said tool to move in the desired curved path.

3. In a device for the generation of curved gear teeth, the combination with the wheel blank, of a stationary member adjustable in relation thereto, an arm pivotally mounted upon said stationary member and adapted to oscillate about a fixed axis thereon, a tool holder slideable along said arm, guide-members for said tool-holder a rack tool carried by said tool holder to act upon said wheel blank, and an interchangeable cam carried by said stationary member and adapted to act upon said tool holder during its oscillatory movement, thereby to cause said tool to sweep out a desired curved path.

In testimony whereof I affix my signature.
HERBERT EDGAR TAYLOR.
